SLIPPER SOCK

Robert S. Servin, Jenkintown, Pa., assignor to Robert Hosiery Mills, Inc., Trappe, Pa., a corporation of Pennsylvania

Filed Oct. 21, 1960, Ser. No. 62,560

Term of patent 14 years

(Cl. D7—7)

FIG. 1

FIGURE 1 is a side elevational view of a slipper sock showing my new design as it appears when in flattened position;

I claim:

The ornamental design for a slipper sock, as shown and described.
